ABSTRACT: An absorption refrigeration system employing a pair of staged air-cooled absorbers and a pair of staged adiabatic evaporators. Strong solution from the generator passes first to the low-pressure absorber from which it flows through the high-pressure absorber back to the generator. Refrigerant liquid is flash-cooled in the high-temperature adiabatic evaporator stage from which it passes to the low-temperature adiabatic evaporator for further flash-cooling and from which it is passed through a refrigerant heat exchanger for cooling a refrigeration load and back to the high-temperature adiabatic evaporator. The system further embodies a scoop pump for circulating solution to and from the absorber and generator which includes a hermetic housing formed with an annular embossment and mounting therewithin a rotatable trough provided with an annular flange which cooperates with the embossment to provide a hydrodynamic seal dividing the interior of the housing into high-pressure and low-pressure zones.

ATTORNEY

ABSORPTION REFRIGERATION SYSTEM

BACKGROUND OF THE INVENTION

This invention relates to absorption refrigeration systems and to pumps used therein. It is known to employ separate centrifugal pumps to circulate strong absorbent solution to an absorber and to also circulate weak absorbent solution from the absorber through a solution heat exchanger to the generator. It has also been proposed to circulate absorbent solution in an absorption refrigeration system by using one or more scoop pumps generally taking the form of a closed chamber within which is rotatably mounted a rotatable pan for centrifugally impelling liquid directed into the chamber through an inlet conduit. The liquid is picked up by a scoop or eduction tube disposed in the pan. Scoop pumps have among their advantages simplicity of construction and will not cavitate significantly even through a relatively small quantity of fluid is fed to them. Further, scoop pumps have other advantages, such as elimination of the requirement for suction head, the ability to pump mixtures of noncondensables and liquids, and can be run with no liquid therein if required, without deleterious results.

It is desirable for reasons of simplicity of construction that the interior of the scoop pump housing be constructed to essentially balance the pressure difference between the absorber and generator so that a single pump having a plurality of pans can be used to satisfy all the pump requirements of the system. Mechanical seals are subject to wear and leakage and can prove troublesome to keep in alignment. They may also impose excessive friction forces which increase cost and decrease efficiency of the pump. Consequently, a need exists for seal means of relatively simple and yet highly reliable construction for dividing the pump housing interior into what may be termed relatively high- and relatively low-pressure zones.

SUMMARY OF THE INVENTION

In accordance with this invention, there is provided an air-cooled absorption refrigeration machine which may be of the type having single or multiple evaporator and absorber stages.

The solution is passed between the absorber and generator by the fluid transfer apparatus, preferably taking the form of a stationary housing member mounting therewithin a plurality of scoop pumps. The pumps include a plurality of rotatable pan members. One of the members is provided with an annular flange received in an annular liquid-filled trough formed on the other member to provide a rotating hydrodynamic seal which balances the pressure difference between the absorber and generator or between other different pressure locations in the system at which the pump may be required to operate.

BRIEF DESCRIPTION OF THE DRAWINGS

FIG. 1 is a schematic flow diagram, partially in cross section, of an absorption refrigeration machine embodying a fluid transfer apparatus in accordance with this invention; and

FIG. 2 is a fragmentary cross-sectional view illustrating a modified pump seal arrangement.

DESCRIPTION OF THE PREFERRED EMBODIMENT

In accordance with a preferred embodiment of this invention, there is provided an absorption refrigeration system which utilizes water as a refrigerant and an aqueous solution of lithium bromide as an absorbent. A suitable additive, such as octyl alcohol (2-ethyl-n-hexanol) for heat transfer promotion and suitable corrosion inhibitors may be added to the solution. "Strong solution" as referred to herein, is a concentrated solution of lithium bromide, which is strong in absorbing power, and "weak solution lithium bromide which is weak in absorbing power. "Intermediate solution" refers to solution intermediate in absorbing power and concentration between strong and weak solutions.

Referring to the drawing, there is shown an absorption refrigeration system comprising a generator 10, a refrigerant

condenser 11, a high-temperature adiabatic evaporator 12, a low-temperature adiabatic evaporator 13, a high-pressure absorber 14, a low-pressure absorber 15, a sensible refrigerant heat exchanger 16, an absorbent solution heat exchanger 17, and solution transfer apparatus A connected to provide refrigeration. A purge unit 18 may be employed to remove relatively noncondensable vapors from the system from any convenient location.

Generator 10 comprises a boiler preferably having a shell 10, 25, a plurality of internal flue tubes 26, a heat source such as gas burner 27, and a flue gas collector 28. Weak absorbent solution enters the generator and is boiled therein to concentrate the absorbent solution by vaporizing refrigerant. The concentrated or strong solution is discharged from the generator through strong solution passage 30. Other types of well-known boilers or generators employing either a combustible fuel, or a heating fluid, such as steam or water, may be employed for concentrating the absorbent solution.

The strong solution leaving the generator is preferably cooled by passing through the shell side passage of solution heat exchanger 17. In the preferred embodiment, fluid transfer apparatus A is employed to pass the strong solution from heat exchanger 17 to the low-pressure absorber.

Low-pressure absorber 15 preferably comprises a plurality of vertically disposed finned absorber tubes 36, opening at their upper ends into a low-pressure vapor header 35. Strong solution is discharged from strong-solution passage 136 into vapor header 35 of low-pressure absorber 15. The lower ends of absorber tubes 36 open into a low-pressure liquid header 38. A fan 39 is preferably disposed adjacent absorber tubes 36 for passing ambient cooling air over the exterior surfaces of the absorber tubes of both the high and low-pressure absorbers to cool absorbent solution passing down through the tubes. While the preferred embodiment of this invention is directed to an air-cooled absorption refrigeration system, a liquid-cooled absorber employing cooling tower water for cooling the absorbent solution, may be used instead of the air-cooled arrangement illustrated.

40 The upper ends of absorber tubes 36 are shown projecting upwardly into vapor header 35 to form a weir for distributing the strong solution onto the interior walls of the absorber tubes. The strong solution passes downwardly through absorber tubes while being cooled by ambient air passing over the exterior surfaces of the tubes, thereby maintaining a low solution vapor pressure or saturation temperature. Refrigerant vapor from low-temperature evaporator 13 enters the ends of absorber tubes 36 from vapor header 35 and passes downwardly therein, concurrently with the strong solution. 45 50 This refrigerant vapor contacts the strong absorbent solution within absorber tubes 36, and is absorbed therein, thereby forming absorbent solution of intermediate strength.

The intermediate solution is collected in liquid header 38 from which it passes through a siphon tube 40 having an upwardly arched portion 41 and a downwardly extending leg 42. The upwardly arched portion 41 of siphon tube 40 opens into liquid header 38 and the downwardly extending leg 42 opens into conduit 45 leading to the solution transfer apparatus.

60 High-pressure absorber 14 is similarly provided with a plurality of vertically disposed finned absorber tubes 46 having their upper ends opening into a high-pressure vapor header 47 to establish a level of intermediate strength absorbent solution therein. The lower ends of the high-pressure absorber tubes 46 open into high-pressure liquid header 48. Intermediate strength absorbent solution from liquid header 47 together with refrigerant vapor from high-temperature evaporator 12 flows downwardly through absorber tubes 46 while the absorbent solution is cooled therein by fan 39 passing ambient air 65 70 over the exterior surfaces of the absorber tubes.

The absorption of refrigerant vapor into the intermediate solution passing downwardly through absorber tubes 46 dilutes the intermediate solution and the resulting weak solution is collected in liquid header 48. Weak solution passes out 75 of liquid header 48 through siphon tube 50 having an up-

wardly arched portion 51 and a downwardly extending leg 52, which forms a liquid seal to prevent escape of some of the refrigerant vapor from the high-pressure absorber. Weak solution passes from siphon tube 50 into weak-solution reservoir 61. Weak solution from reservoir 61 passes through passage 138 and is forwarded by solution transfer apparatus A through weak-solution passage 140 and the interior passage of solution heat exchanger 17 through passage 63 to generator 10 for reconcentration.

The refrigerant vapor formed by boiling weak solution passes out of the generator through refrigerant vapor line 65 into vapor header 70 of refrigerant condenser 11. Refrigerant condenser 11 preferably comprises a plurality of vertically disposed finned condenser tubes 71 opening upwardly into vapor header 70 and downwardly into liquid header 72. Cooling air is passed over the exterior surfaces of finned tubes 71 by a suitable fan such as fan 39. The refrigerant vapor is condensed within condenser tubes 71 by heat exchange with the air and the condensed refrigerant passes through the refrigerant liquid line 74 into the high-temperature refrigerant evaporator 12.

High-temperature adiabatic evaporator 12 may comprise a shell 80 from which a refrigerant vapor passage 86 extends to vapor header 47 of the high-pressure absorber. The warm refrigerant, upon entering high-temperature evaporator 12, is adiabatically flash-cooled to the corresponding absorber pressure and saturation temperature. The unevaporated major portion of liquid refrigerant in adiabatic evaporator 12 is cooled due to flashing of a portion of the refrigerant therein.

The cooled refrigerant liquid reaching the bottom of the high-temperature adiabatic evaporator is discharged by gravity through cool refrigerant line 85, having a liquid trap 87, into low-temperature adiabatic refrigerant evaporator 13. Trap 87 provides a liquid seal between the high-temperature and low-temperature adiabatic evaporators to prevent the passage of a substantial quantity of vapor between them and to maintain the pressure difference between the evaporator stages.

The cooled refrigerant discharge from the high-temperature adiabatic evaporator 12 into the low-temperature adiabatic evaporator 13 is again adiabatically flash-cooled to a still lower temperature. The cold refrigerant liquid reaching the bottom of low-temperature adiabatic evaporator 13 is discharged by gravity flow through cold refrigerant liquid passage 95 into a suitable refrigerant reservoir 96, which is vertically below and may be integrally formed with the low-temperature evaporator.

The cold-liquid refrigerant is then pumped by a refrigerant pump 97 in refrigerant liquid line 98 through refrigerant heat exchanger 16. Refrigerant heat exchanger 16 comprises a sensible heat exchanger for cooling the desired refrigeration load, which, in the illustrated embodiment, is air passing by means of fan 103 through duct 104 in sensible heat exchange relation with the refrigerant passing through refrigerant heat exchanger 16. The warmed liquid refrigerant, having absorbed heat from the refrigeration load, returns to the high-temperature evaporator through refrigerant line 105.

Fluid transfer apparatus A of this invention comprises a stationary hermetic housing 110 formed on its circumference with an annular embossment 111 defining interiorly of the housing a circumferentially extending, radially inwardly opening, concave groove or trough 112. Within the housing 110 there is mounted scoop pump means comprising a central partition member 113 mounted by means of a collar member 114 upon cylindrical shaft 115 forming an outer shell of drive means 116. Shaft 115 is journaled in bearing means 117 and 118, and interiorly of the housing 115 is a pair of axially spaced magnets 119 and 120, the magnet 119 being connected to shaft means 121 driven by motor means 122.

The central partition member 113 has secured thereto an annular flange 123 having a pair of radially inwardly directed flange sections 124 and 125. Radially inwardly spaced from the annular member 123 is an annular wall member 126 hav-

ing a radially inwardly directed flange section 127 attached thereto. Annular wall member 123 is spaced radially inwardly of the outer circumference of the partition member 113 so as to provide protruding annular flange or wall portion 128 received in the annular cavity or groove 112 to define therewith a rotating hydrodynamic seal. The annular wall member 123 and the radially inwardly directed wall sections 125 define with the central partition 113 and housing interior a pair of scoop pump pans forming chambers C-1 and C-2, while the annular wall member 126 and its radially inwardly directed flange portion 127, in cooperation with the central partition 113 and housing interior, define a third scoop pump pan forming solution circulation chamber C-3.

The solution circulation chamber C-1 receives therein discharge nozzle 130 of conduit means 45 leading from liquid header 38 of low-pressure absorber 15 for transferring to the compartment C-1 solution of intermediate concentration. Leading into this same chamber is eduction orifice 131 of conduit means 132 which functions to pump intermediate solution to high pressure absorber 14.

The chamber C-3 has disposed therein discharge nozzle 133 of conduit means 134 communicating through solution heat exchanger 17 with conduit 30 to feed to chamber C-3 strong solution from generator 10. Chamber C-3 also has disposed therein eduction orifice 135 of conduit means 136 for transferring to low-pressure absorber 15 strong solution from chamber C-3.

Solution circulation chamber C-2 receives therein discharge nozzle 137 of conduit means 138 which communicates with reservoir 61 to drain into chamber C-2 weak solution which is pumped therefrom by eduction orifice 139 of conduit means 140 communicating through solution heat exchanger 17 and conduit 63 to transfer to generator 10 weak absorbent solution for reconcentration therein.

Chamber C-1 also has disposed therein inlet orifice 141 of pickup scoop 142 functioning to transfer to this chamber liquid which splashes into the bottom of housing 110 during operation or which drains into the bottom of the housing 110 upon machine shutdown.

The flange portion 128 on the central partition 113, in cooperation with the embossment 111 on the housing 110, divides the interior of the housing into a relatively low-pressure zone in chamber C-2 and a relatively high-pressure zone in chambers C-1 and C-3. These pressures are balanced by the difference in height of the liquid in the rotating hydrodynamic seal provided by this invention because the sides of trough 112 overlap flange 128 a substantial extent. It is to be seen that conduit 134 has a restriction 143 therein and that conduit 45 is also provided with a restriction 144. Strong solution draining into chamber C-3 through conduit 134 from generator 10 flash-cools down to absorber vapor pressure by reason of being exposed to intermediate concentration solution in chamber C-1.

FIG. 2 illustrates another type of hydrodynamic seal which can be utilized in accordance with this invention to provide a relatively frictionless liquid seal between radially spaced chambers C-1 and C-3. In this embodiment, pump housing member 210 is provided with a radially outwardly extending flange member 211, and rotatable wall 213 is provided with a radially inwardly opening trough 227 into which flange 211 extends. Trough 227 is secured with and forms a part of pan member 226 and flange 211 is secured with and forms a part of housing member 210. When pan member 226 is rotated, liquid in trough 227 assumes a height on either side of flange 211 sufficient to balance the difference in pressure between chambers C-1 and C-3.

The arrangement described is particularly advantageous because an effective seal is provided without the necessity of maintaining a precise alignment between the rotating and stationary parts and which is capable of providing effective sealing even through clearances may change due to bearing wear. Furthermore, the seal provided is relatively friction free, automatically compensates for differences in pressure and unlike

mechanical seals is not subject to wear. Since the liquid in the seal is essentially a rotating liquid annulus, whether the trough be stationary or rotating, there is a centrifugal component of force acting on the liquid which permits a given pressure difference to be balanced by a relatively small difference in height of the liquid column on either side of the flange member. Furthermore, on machine shutdown, the seal may be broken and the liquids are enabled to intermix in the bottom of the housing to form an antifreeze mixture having a relatively low solidification temperature. The apparatus may also be utilized in either a vertical or horizontal axial plane by suitable design.

Various other modifications may be made within the scope of the following claims.

I claim:

1. An absorption refrigeration system comprising a generator for concentrating absorbent solution by vaporizing refrigerant therefrom to form strong absorbent solution; a condenser connected for condensing refrigerant vapor formed in said generator; an evaporator for evaporating the refrigerant liquid therein; and absorber connected to the evaporator for absorbing refrigerant vapor formed therein; and a fluid transfer apparatus comprising; a stationary hermetic housing member; a first scoop pump in said housing member comprising a rotatable pan member, a first inlet passage disposed for supplying liquid to said pan member and a first eduction conduit having an eduction orifice disposed in said pan; a second scoop pump in said housing comprising another rotatable pan member, a second inlet conduit disposed for supplying liquid to said other pan and a second eduction conduit having an eduction orifice disposed in said

other pan; and a liquid seal between said first and second scoop pumps, said seal comprising an annular trough adapted to contain liquid secured with a first one of said members and an annular flange secured with a second one of said members extending into said trough to contact liquid therein, said first and second members being rotated relative to each other when said pan members are rotated, said liquid serving to inhibit the passage of vapor from one pan of said scoop pump to the other pan thereof during relative rotation of said first and second members.

2. An absorption refrigeration system as defined in claim 1 wherein said trough comprises an annular, radially inwardly open groove in said housing member, said flange extending radially outwardly from at least one of said pans into said trough to form a liquid seal therewith when said trough contains liquid.

3. An absorption refrigeration system as defined in claim 1 wherein the first scoop pump is exposed to absorber pressure and the second scoop pump is exposed to generator pressure, said seal having a radial dimension sufficient to balance the difference in pressure between said pans with a column of liquid in said trough on one side of said flange.

4. An absorption refrigeration system as defined in claim 1

25 wherein said trough comprises an annular radially inwardly open portion of one of said pan members, and said flange extends radially outwardly from said housing into said trough to form a liquid seal with the liquid in said pan when said trough contains liquid during operation of said fluid transfer apparatus.
